PROCESS FOR PRODUCING AROMATICS

William J. Mattox, Riverside, Ill., assignor to Universal Oil Products Company, Chicago, Ill., a corporation of Delaware

Application March 12, 1943, Serial No. 478,920

5 Claims. (Cl. 260—673.5)

This invention relates to the production of aromatic hydrocarbons and/or improved motor fuel of low bromine number. More specifically, the invention relates to the treatment of a selected fraction of an olefin-containing-distillate, the olefin-containing-distillate being defined as a hydrocarbon distillate containing varying percentages of olefin hydrocarbons along with other types of hydrocarbons such as paraffins, naphthenes and/or aromatics.

It has heretofore been shown that olefin hydrocarbons containing six or more carbon atoms in straight chain arrangement may be dehydrogenated and cycled into aromatic hydrocarbons in the presence of suitable catalysts and under selected conditions of operation. However, when the paraffin charging stock to the aromatization (dehydrogenation-cyclization) process contains olefin hydrocarbons an excessive deposition of carbon on the catalyst results. This is exemplified in hereinafter described Example I in which the aromatization of an olefin-containing-distillate produced 11.2% of carbon by weight based on the charge to the aromatization process as contrasted to only 5.96% by weight of carbon in a comparable run in which the charge thereto was first pretreated in accordance with the features of the present invention.

It is obvious that a reduction in carbon to slightly less than half is of tremendous importance in the efficient operation of an aromatization process. This reduction in carbon formation minimizes the time required for regenerating the catalyst by the removal of the carbon therefrom and also greatly reduces the size and cost of the regenerating equipment.

In a broad aspect, the present invention comprises subjecting an olefin-containing distillate to a deolefination treatment, separating a selected fraction from the products of the deolefination, and subjecting the separated fraction to an aromatization treatment.

In another aspect, the invention comprises a process for increasing the antiknock characteristics and reducing the bromine number of an olefin-containing distillate by subjecting said distillate to a deolefination treatment, separating a selected fraction from the products of the deolefination, and subjecting the separated fraction to an aromatization treatment.

In a specific embodiment the invention relates to a process for producing aromatic hydrocarbons and high antiknock motor fuel of low bromine number which comprises cracking oil, separating a fraction boiling within the range of

gasoline from the products of said cracking, subjecting the separated fraction to a deolefination treatment, separating the products of deolefination into a low bromine number fraction boiling within the range of gasoline and a higher boiling fraction containing aromatics, recycling said higher boiling fraction to said cracking, and subjecting said low bromine number fraction to an aromatization treatment.

- 10 Deolefination of an olefin-containing distillate may be effected in the presence of an acid-acting oxygen compound of phosphorus at a temperature of from about 250° to about 750° F. and preferably of from about 350° to about 600° F.
- 15 under sufficient pressure to maintain at least a substantial portion of the material in the reaction zone at the conditions of operation in liquid phase. Such a process is usually conducted at a space velocity of from about 0.5 to about 10, the space velocity being defined as the weight of charge per hour per unit weight of catalyst in the reaction zone. Satisfactory but not necessarily equivalent catalysts include phosphorus pentoxide, ortho-phosphoric acid, pyro-phosphoric acid, 25 copper pyrophosphate, cadmium pyro-phosphate, etc., which may be employed either alone or in admixture with a suitable supporting material such as kieselguhr, pumice, bentonite, bauxite, and other siliceous and aluminous materials.
- 30 Another suitable but not necessarily equivalent method of deolefination is to subject the olefin-containing distillate to contact with a silica base catalyst under selected conditions of operation. The silica base catalyst comprises various associations of silica with one or more compounds of elements whose oxides are refractory, such as alumina, zirconia, magnesia, thoria, ceria, etc. These catalysts may be synthetically prepared or they may comprise certain naturally occurring materials such as bentonite, montmorillonite, flордин, etc., the alternative catalysts not necessarily being equivalent in their activity. These catalysts are usually employed at a temperature of below about 1000° F. and more generally at a temperature of below about 950° F. In one method of operation, the catalyst may be employed at a temperature of from about 400° to about 700° F. under sufficient pressure to maintain at least a substantial portion of the material in the reaction zone in liquid phase. Vapor or mixed phase operations may be employed when utilizing higher temperatures in the reaction zone. The weight space velocities usually employed may range from about 0.3 to about 15.
- 45 55 The aromatization of hydrocarbons containing

six or more carbon atoms in straight chain arrangement may be effected in the presence of suitable catalysts and may comprise, for example, an aluminous and/or siliceous compound composited with a compound and preferably an oxide of the elements in the left hand columns of groups IV, V and VI of the periodic table. A particularly suitable catalyst comprises alumina composited with chromia or alumina composited with molybdena. It is understood that these catalysts are not necessarily equivalent in their activity for effecting the desired reaction. The temperatures normally employed with these catalysts are within the range of about 900° to about 1100° F. and preferably are between about 950° to about 1000° F. It is understood that the aromatization step includes not only the cyclization of the aliphatic hydrocarbons but also includes the dehydrogenation of any naphthenic hydrocarbons contained in the charging stock to this step of the process.

The selected fraction to be separated from the products of the cracking and deolefination steps for processing in the successive step of the process will depend upon the final products desired. For example, if it is desired to produce primarily benzene as the final product of the process, the selected fraction subjected to conversion in the deolefination and/or aromatization treatment may comprise a fraction boiling substantially within the range of hydrocarbons containing six carbon atoms to the molecule. Likewise, if it is desired to produce primarily toluene, the selected fraction may comprise constituents boiling substantially within the range of hydrocarbons containing seven carbon atoms to the molecule. Usually, however, the selected fraction will not be of such narrow boiling range but will include constituents boiling above and below the particular hydrocarbons and may comprise for example, a selected fraction boiling from about 185° to about 255° F. when toluene is the desired aromatic. If motor fuels are the desired product, the selected fraction may have a boiling range of from about 80° to 400° or even 500° F. more or less. Usually the boiling range of the fraction subjected to aromatization will be the same or of narrower boiling range than the fraction subjected to deolefination.

The olefin-containing charging stock to the deolefination step of the process may suitably comprise cracked gasoline. This gasoline contains a mixture of olefins and paraffins as well as other hydrocarbons such as naphthenes and aromatics. Cracking may be either non-catalytic or it may be catalytic and, in the latter case, any suitable well known cracking catalyst may be employed. In still another embodiment, the olefin-containing charging stock may comprise a reformed gasoline and, in this case, usually but not necessarily, it will be one that is produced in a non-catalytic operation.

The invention is further explained, in connection with the attached diagrammatic flow drawing which illustrates one specific embodiment of the invention.

Referring to the drawing, the charging stock in this case comprises crude oil and is introduced to the process through line 1 into separation zone 2 which may comprise one or a plurality of suitable fractionation, distilling, absorbing and separating zones whereby the material charged thereto may be separated into the desired fractions. Normally gaseous hydrocarbons may be withdrawn through line 3 from zone 2. Line 4 is

provided for withdrawing a selected fraction, which may be of relatively narrow boiling range or a full boiling gasoline. This fraction may be supplied to the aromatization step of the process as will hereinafter be described in detail or all or a portion thereof may be withdrawn from the process through an extension of line 4.

The material boiling above the selected fraction may be withdrawn through line 6 and supplied to the cracking step of the process or, if desired, the higher boiling material may be withdrawn from the process through an extension of line 6, while a selected fraction of the higher boiling material may be withdrawn from zone 2 through line 5 and directed to the cracking step of the process.

Cracking zone 9 may be either catalytic or non-catalytic as heretofore mentioned. If this zone is a non-catalytic cracking operation, the total higher boiling material withdrawn through line 6 may be directed through lines 7 and 8 into zone 9 for conversion therein. When zone 9 comprises a catalytic cracking operation it is preferable to supply a selected fraction such as gas oil, which may be withdrawn from zone 2 through line 5 and directed through line 8 into zone 9 for conversion therein.

Cracking zone 9 may comprise any suitable type of cracking operation. The products from zone 9 are directed through line 10 into separation zone 11 which may be similar to zone 2 as heretofore described. Line 12 is provided for withdrawing normally gaseous hydrocarbons and any normally liquid hydrocarbons boiling lower than the components desired in the selected fraction which is withdrawn from zone 11 through line 13. Line 14 is provided for the withdrawal of material boiling above the components desired in the selected fraction, and all or a portion of the higher boiling material may suitably be recycled by way of lines 14, 15 and 8 to zone 9 for further conversion therein, while any material not so recycled may be withdrawn from the process through an extension of line 14.

The selected fraction withdrawn through line 13 is directed into deolefination zone 16 which may be of any suitable type so that the products withdrawn therefrom will have a lower bromine number than the products introduced thereto. The bromine number of the products emitting from zone 16 is preferably reduced to less than half that of the charging stock supplied to zone 16. The reactions occurring in zone 16 are not completely understood but it is known that the products emitting therefrom will contain material boiling substantially within the same range as the charging stock to the deolefination step, which material will have a considerably reduced bromine number, and higher boiling material, which higher boiling material will contain aromatic hydrocarbons varying from 40 to 70% or even higher of the total higher boiling products.

The products from zone 16 are directed through line 17 into separation zone 18 which may be similar to heretofore described zone 2. Line 19 is provided for the withdrawal of components boiling below those desired in the selected fraction which is withdrawn from zone 18 through line 20. Products boiling above the selected fraction are withdrawn from zone 18 through line 21 and may be removed from the process but preferably, in accordance with the features of the present invention, at least a portion of the higher boiling material is directed through line 22 and recycled within the process for conversion into lower boil-

ing aromatic hydrocarbons. This may be accomplished by directing a portion of the higher boiling material through lines 22, 23 and 16 into zone 11 wherein they are separated with the higher boiling products of the cracking operation and recycled by way of lines 14, 15 and 8 to cracking zone 9, or the higher boiling material withdrawn through line 21 may be supplied through lines 22, 24, 7 and 8 directly to zone 9.

Deolefination zone 16 not only serves to reduce the bromine number of the selected fraction but also serves to produce higher boiling aromatic hydrocarbons, which higher boiling aromatic hydrocarbons are recycled to the cracking step and therein converted into additional quantities of lower boiling aromatic hydrocarbons desired as the final product of the process. Thus the deolefination step serves to increase the yield of desired aromatic hydrocarbons.

The selected fraction withdrawn through line 20 from zone 18 is directed into aromatization zone 25. When desired, the selected fraction withdrawn through line 4 from zone 2 may be directed through line 26 into zone 25 for conversion therein in commingled state with the selected fraction introduced thereto through line 20. Aromatization zone 25 may be of any suitable type in order to effect the desired reaction. The exact conditions of operation will depend upon the particular selected fraction introduced through line 20, but the condition of operation will be within the range heretofore specified. The aromatization products are withdrawn from zone 25 through line 26' and are directed into separation zone 27 which may be similar to zone 2 heretofore described.

Normally gaseous hydrocarbons may be withdrawn from zone 27 through line 28 and may be removed from the process or, when desired, a regulated portion of these gases may be recycled by way of lines 29 and 30 to zone 25. This recycling is usually employed when it is desired to conduct the aromatization step in the presence of hydrogen, similar to the process now known as hydroforming. Hydrogen from an extraneous source may be introduced to this step of the process through an extension of line 30. When desired, the gaseous products withdrawn through line 28 may be subjected to any suitable pretreatment not illustrated, in order to concentrate the hydrogen prior to recycling to zone 25. It is also within the scope of the invention to separate the hydrogen from the gaseous products withdrawn through line 12 from zone 11 and supply all or a portion of the hydrogen so separated to zone 25, as desired.

Material boiling above the range of motor fuel is withdrawn from zone 27 through line 29' and preferably all or a portion thereof is recycled by way of lines 24, 7 and 8 to cracking zone 9 for further conversion therein.

Line 32 is provided for the withdrawal of selected aromatic hydrocarbons such as benzene, toluene, etc., from zone 27, while line 33 is provided for the withdrawal of motor fuel. If it is desired to separate several particular aromatic hydrocarbons as well as motor fuel, it is understood that the separation may be effected either in zone 27 or by any other suitable separation means. The aromatic hydrocarbons so separated will be of high purity, and the motor fuel so separated will be of high aromatic content and of low bromine number, and thus will be particularly suitable for use in the production of aviation gasoline.

The following examples are introduced for the purpose of further illustrating the novelty and utility of the present invention but not with the intention of unduly limiting the same.

Example I

A naphtha having a boiling range of from 184 to 255° F. and a bromine number of 77, was separated from the products of thermal cracking. 10 This cracked naphtha was subjected to deolefination at a temperature of 527° F. under a pressure of 800 pounds per square inch in the presence of a solid phosphoric acid catalyst. The liquid products recovered amounted to 97.8% by weight of the charge and these liquid products were fractionated to separate 58.5% by volume of a selected fraction having a boiling point of 185 to 254° F. and a bromine number of 28. The deolefined selected fraction was then subjected to aromatization at 977° F. and atmospheric pressure in the presence of an alumina-chromia catalyst.

For comparative purposes, another sample of the cracked naphtha without the deolefination pretreatment was subjected to aromatization under the same conditions as described above. The results of aromatization for both the untreated and the pretreated naphthas are summarized below:

		Untreated naphtha	Treated naphtha
	Naphtha:		
35	Boiling range, °F.	184-255	185-254
	Bromine number	77	28
	Yields, weight per cent of charge:		
	Total liquid hydrocarbons	83.7	85.4
40	Gas	6.8	6.7
	Carbon	11.2	5.96
	Grams, aromatics per gram of carbon	1.97	3.42
	Aromatic fraction:		
45	Boiling range, °F.	122-275	122-279
	Weight per cent of total liquid recovery	94.4	95.3
	Weight per cent of charge	79.0	81.4

It is thus seen that the carbon produced during the aromatization step was 5.96% for the deolefined naphtha as compared to 11.2% for the untreated naphtha.

Example II

A cracked naphtha having a boiling range of 185 to 257° F. and a bromine number of 77 was subjected to deolefination in the presence of a silica-alumina catalyst at a temperature of 527° F. under a pressure of 900 pounds per square inch to yield liquid products amounting to over 99% by weight of the charge. A selected fraction having a boiling range of 185 to 257° F. and a bromine number of 2 may be separated from the products of said deolefination and may then be subjected to aromatization in the presence of an alumina-chromia catalyst at a temperature of 980° F. under atmospheric pressure to produce high yields of toluene.

I claim as my invention:

1. A process for producing aromatics which comprises cracking hydrocarbon oil and separating from the resultant cracked products a distillate containing paraffinic and olefinic hydrocarbons having at least six carbon atoms in straight chain arrangement, reducing the bromine number of said distillate by converting olefins present therein into non-olefinic hydrocarbons boiling substantially within the range of said distillate and also into higher boiling aromatic hydrocarbons, fractionating the distillate 65 to separate said higher boiling aromatic hydro-

carbons therefrom and supplying at least a portion of the latter to the cracking step, and subjecting the fractionated distillate to aromatization in the presence of an aromatizing catalyst under conditions such as to convert paraffins to aromatics. 5

2. The process as defined in claim 1 wherein said olefin conversion treatment is conducted in the presence of a phosphoric acid catalyst at a temperature of from about 250° to about 750° F. 10

3. The process as defined in claim 1 wherein said olefin conversion treatment is conducted in the presence of a catalyst containing silica and alumina at a temperature of from about 400° to about 1000° F. 15

4. A process for producing toluene which comprises cracking hydrocarbon oil and separating from the resultant cracked products an olefinic distillate boiling in the range of from about 185° F. to about 255° F., reducing the bromine number of said distillate by converting olefins present therein into non-olefinic hydrocarbons boiling substantially within the range of said distillate and also into higher boiling aromatic hydrocarbons, fractionating the distillate to separate said higher boiling aromatic hydrocarbons therefrom and supplying at least a portion of the latter to 20

the cracking step, and subjecting the fractionated distillate to aromatization in the presence of an aromatizing catalyst under conditions such as to convert paraffins to aromatics.

5. A process for producing aromatics from crude oil which comprises fractionating the crude to separate therefrom a fraction boiling in the gasoline range and a fraction heavier than gasoline, cracking the last-mentioned fraction and separating from the resultant cracked products a distillate containing paraffinic and olefinic hydrocarbons having at least six carbon atoms in straight chain arrangement, reducing the bromine number of said distillate by converting olefins present therein into non-olefinic hydrocarbons boiling substantially within the range of said distillate and also into higher boiling aromatic hydrocarbons, fractionating the distillate to separate said higher boiling aromatic hydrocarbons therefrom and supplying at least portion of the latter to the cracking step, commingling the fractionated distillate with said fraction boiling in the gasoline range, and subjecting the resultant mixture to the action of an aromatization catalyst under paraffin aromatizing conditions. 25

WILLIAM J. MATTOX.
